UNITED STATES PATENT OFFICE.

ROBERT S. COX, OF TERRE HAUTE, INDIANA.

DUMP-CAR.

SPECIFICATION forming part of Letters Patent No. 476,366, dated June 7, 1892.

Application filed October 22, 1889. Serial No. 327,816. (No model.)

To all whom it may concern:

Be it known that I, ROBERT S. COX, a citizen of the United States, residing at Terre Haute, in the county of Vigo and State of Indiana, have invented certain new and useful 5 Improvements in Dump-Cars, of which the following is a specification.

This invention relates to dump-cars; and it consists in the construction, combination, and 10 arrangement of parts, as hereinafter shown and described, and specifically pointed out in the claims.

In the drawings, Figure 1 is a semi-sectional side elevation, Fig. 2 is a plan view, and Fig. 15 3 is a cross-sectional view on the line $x-x$ of Fig. 1, of one of my dump-cars complete. Fig. 4 is a view similar to Fig. 3, showing a slight modification in the construction.

A' represents the floor-frame, A² the side 20 frames, and A³ the trucks, of a car, these parts being of the ordinary construction, except that the floor is provided with openings a along the sides between the trucks, these openings being covered by downwardly-opening doors 25 or drops B. These doors B are each hinged by one edge to the floor-frame, as shown, and supported by chains D by their free edges, the chains passing upward over rods or windlasses E' to arms E² or to other devices whereby the 30 doors may be elevated or allowed to be depressed. The openings a will generally be arranged between the trucks, so that the material being discharged from the car will not fall upon the axles or truck-frames.

35 In Figs. 1, 2, and 3 the interior of the car-body is formed hopper-shaped by inclined sections F, which cause all the contents to run down through the openings a when the doors B are opened, while in Fig. 4 the interior is 40 without these inclined sections.

45 While the presence of the inclined sections renders the discharge of the contents of the car more convenient, I do not wish to be limited to their use, as the car is operative without them.

The openings a may be of any required size and may be of any desired number, but will occupy the same relative position with relation to the bottom and sides of the car—viz., 50 along the sides—as the location of these openings, and the manner in which they are em-

ployed is one of the principal features of my invention.

This class of dump-cars are employed more particularly in railroad-grading work in transporting earth and similar material and in discharging it quickly at whatever point desired. 55

By arranging the discharge-openings a in the bottom along the sides I am enabled to discharge the material from the cars close to the outside of the track when the doors B are hung by their inner edges, as in Fig. 3, or between the rails when the doors are hung by their outer edges, as in Fig. 4.

In grading railroads the earth is required 65 to be discharged as close to the rails as possible, either inside or outside, to produce the best results and avoid the necessity for re-handling by shoveling or otherwise. In completing "fills" around trestle-work and other 70 similar locations this ability to discharge the earth close to the track or between the rails is of especial advantage, and the extreme simplicity of the construction of my car and the method of accomplishing this result render it 75 of great importance.

The doors B by the method of supporting them serve as "chutes" to the earth when being discharged, so that it is conducted from the car in any desired quantity or with any 80 desired degree of force.

I have shown in Figs. 1, 2, and 4 and the left of Fig. 3 the doors B, adapted to be actuated by chains D, connecting them to horizontal shaft E', the revolution of the rods winding the chains upon the rods as drums, while on the right of Fig. 3 I have shown an arm E², attached to the shaft E', and with a chain D connecting its outer end with the doors B, the revolution of the shaft E' causing the outer 90 ends of the arms to rise and fall and thus open or close the door B; but I do not wish to be limited to any specific method of operating the doors, as I am aware that they may be operated by other suitable devices than those 95 shown.

Having thus described my invention, what I claim as new is—

1. In a dump-car, the combination, with the frame and inclined bottom, of downwardly-opening doors hinged to the bottom, a longitudinally-arranged shaft journaled in the ends 100

of the car above the doors, and chains directly connecting the shaft and free edges of the doors, substantially as and for the purposes described.

5 2. In a dump-car, the combination, with the frame and inclined bottom, of downwardly-opening doors hinged at their inner edges to said bottom, a longitudinally-arranged shaft journaled in the ends of the car in vertical alignment with the free edges of the doors, and chains secured to said free edges and wound around and secured to the shaft, and means for rotating the shaft, whereby the same acts in the capacity of a windlass and any incline given to the doors at the discharge, substantially as and for the purposes described.

15 3. In a dump-car, the combination, with the frame and inclined bottom, of hinged doors forming chutes hinged at their inner edges to

20 said bottom and below the incline thereof, a longitudinally-arranged shaft journaled in the ends of the car in vertical alignment with the free edges of the doors, two or more chains secured to said free edges and wound around and secured to the shaft, and means for rotating the shaft, whereby the same acts in the 25 capacity of a windlass and any incline given to the doors at the discharge, substantially as and for the purposes described.

25 In testimony whereof I have hereunto set my hand in the presence of two subscribing 30 witnesses.

ROBERT S. COX.
